(57) **CLAIM**

The ornamental design for an electric heater, as shown and described.

DESCRIPTION

FIG. 1 is a front view of an electric heater according to my new design;

FIG. 2 is a right side view of the electric heater of FIG. 1, the left side view being a mirror image thereof;

FIG. 3 is a top view of the electric heater of FIG. 1

FIG. 4 is a rear view of the electric heater of FIG. 1; and,

FIG. 5 is a cross-sectional view of the electric heater of FIG. 1 taken at Line 5-5 of FIG. 4.

The broken lines shown in the views depict portions of the electric heater and form no part of the claimed design.
